UNITED STATES PATENT OFFICE.

WILLIAM J. STINSON, OF LONDON, CANADA, ASSIGNOR TO JOHN C. GROSCH, OF LONDON, CANADA.

ACETYLENE-GAS GENERATOR.

SPECIFICATION forming part of Letters Patent No. 757,577, dated April 19, 1904.

Application filed December 23, 1901. Serial No. 87,031. (No model.)

To all whom it may concern:

Be it known that I, WILLIAM J. STINSON, a citizen of the United States, and a resident of the city of London, in the county of Middlesex, in the Province of Ontario, Canada, have invented a certain new and useful Gas-Machine, of which the following is a specification.

This invention relates to a machine for generating acetylene gas; and it consists of the improved construction and novel combination of parts, as will be hereinafter first fully set forth and described and then pointed out in the claims.

Reference being had to the accompanying drawings, Figure 1 is a central longitudinal sectional view of a gas-machine embodying my invention. Fig. 2 is a detail plan view of the generator, showing a battery or series of carbid-cases and attachments. Fig. 3 is a detail plan view of the roller shown in Fig. 2. Fig. 4 is a detail central cross-sectional view of the carbid-case and also of the carbid-holder contained therein. In this view a cross-sectional view of a guide, as well as a portion of the guiding and conducting pipe, is shown. Fig. 5 is a horizontal sectional view on the line *a a* of Fig. 4. Fig. 6 is a perspective view of the carbid-holder.

In the accompanying drawings the numeral 30 1 designates the generator-tank, which is divided into two chambers 2 and 3 by the inclined partition 4, and said chambers 2 and 3 are filled with water to the height indicated by the dotted lines 5 and 6, respectively; but 35 the inclined partition or bottom 4 is watertight and prevents the water from one chamber passing into the other, and 2^a is a valve or gate which permits the removal of ash or other residue from the chamber 2.

40 7 designates a U-shaped pipe having one end inside the compartment 3 and the other end terminating outside of the water-tank. This pipe is for the purpose of maintaining the water-level in the chamber 3.

45 8 designates a pipe extending from near the top of the chamber 2 into the chamber 3, and said pipe 8 extends slightly below the water-level 6 in said chamber 3.

9 designates a carbid-case closed at the up-

per end and open at the lower end, and secured to two sides of which and extending in a curved shape or handle above is the pipe 10, and 50 11 is an opening in the carbid-case 9, which permits the gas to pass from the carbid-case 9 to the pipe 10, and when said carbid-case 9 is placed in proper position in the generator-tank 1 the pipe 8 telescopes the pipe 10 at one side of the carbid-case, as shown in Fig. 1.

9^a designates a carbid-holder open at both 60 ends and provided with a central partition 9^b, on which the carbid is placed.

9^c designates perforations formed in the upper portion of the sides of the carbid-holder, and 9^d designates a catch supported in the carbid-case 9, the lower angular end 9^e of which may be adjusted under said carbid-holder 9^a to secure the latter in said carbid-case 9 when desired.

12 designates an inwardly-extending guid-ing-flange secured to the inside of the generator-tank 1, and 13 represents curved recesses formed in said flange 12, to which the pipe 10 on the adjacent side of the carbid-case 9 is fitted and with which it is adapted to engage. This 70 pipe 10 on one side of the carbid-case, being fitted to and adapted to engage with the recess 13 in the guiding-flange 12 and the pipe 8 tele-scoping with said pipe 10 at the opposite side of the carbid-case 9, holds the latter in line or 80 in an upright position when it is automatically lowering itself in said generator-tank 1.

14 designates a shoulder formed integral with or secured to the pipe 10.

15 designates a sliding bar provided with a 85 flange 16 at one end and with lugs 17 on the other end, in which lugs 17 the antifriction-roller 18 is pivotally secured.

19 designates a plate secured to the top of the generator-tank 1, and 20 designates a 90 holder through which the sliding bar 15 ex- tends, and said holder 20 holds said sliding bar 15 in place and in line with the shoulder 14 on the pipe 10 as said sliding bar is ad- justed back and forth, and 15^a designates anti-friction-rollers mounted in the holder 20 and 95 adapted to engage with the opposite sides of the sliding bar 15.

21 designates a shaft provided with pins 22, which are arranged in a helical curve around said shaft, and 23 designates a ratchet-wheel rigidly secured to said shaft.

5 24 24 designate brackets secured to the generator - tank 1 or other suitable support, in which the shaft 21 is supported and rotates perfectly free.

25 is a bracket secured to the gasometer 26, and 27 is a ratchet-bar pivotally secured to and suspended therefrom and adjusted to engage with the teeth of the ratchet-wheel 23.

28 designates a water-tank filled with water to the height indicated by the dotted line 29, in which tank 28 the gasometer 26 is vertically movable.

30 30 designate stop-rods secured to the water-tank 28, which arrest the movement of the gasometer in order to prevent the lower end 20 of the latter from rising out of the water in the water-tank 28.

31 designates a water-sealing chamber located below the water-tank 28 and provided with a lip 32 for refilling or for overflow.

25 33 designates a gas-inlet pipe opening into and extending from the chamber 3 of the generator-tank 1 to the gasometer 26.

34 designates a hood secured to the upper end of the gas-inlet pipe 33, the lower edge of 30 which hood extends a short distance into the water in the tank 28, and said gas-inlet pipe 33 opens into said hood above the water in said tank 28, and 35 designates a branch of 35 said gas-inlet pipe 33, which extends a short distance into the water in the water-sealing chamber 31.

36 designates a tube in which the opening or openings 37 are formed, and said tube is rigidly secured to the top of the gasometer 26.

40 38 designates a service - pipe which opens into the tube 36 above the water in the water-tank 28, and said service-pipe 38 extends to the burners and is provided with a branch 39, which extends for a short distance into the
45 water in the water-sealing chamber 31.

40 designates a tube rigidly secured to the gasometer 26, and 41 designates a safety-pipe rigidly secured to the bottom of the water-tank 28, which extends upward in or telescopes with 50 said tube 40.

42 designates a secondary or supplemental safety - pipe which extends from the water-sealing chamber 31 to the outside of the building.

55 43 designates a pipe which connects said secondary safety-pipe 42 with the service-pipe 38, and said connecting-pipe is provided with a valve 44.

The operation is as follows: A case 9 of car-
60 bid having dropped into the chamber 2 of the generator-tank 1, it is completely submerged in water, and the water coming in contact with the carbid in said case 9 gas will be generated, which passes out of said case 9 through opening 11 and into and through pipes 10 8, and
65

from the latter it bubbles up through the water into the chamber 3, and said gas is then conducted by the gas-inlet pipe 33 to the hood 34, and from the latter it again bubbles up through the water into the gasometer 26, which causes 70 the latter to rise. As the gas is consumed said gasometer 26, as well as the ratchet-bar 27, is lowered, and as said ratchet-bar 27 is lowered it engages with the ratchet-wheel 23 on the shaft 21 and rotates the latter, together with 75 the pins 22, and as said shaft revolves one of said pins 22 engages with the shoulder 16 on the sliding bar 15 and adjusts the latter from in under the shoulder 14 on the pipe 10. The succeeding carbid-case to which said pipe 10 80 is attached then drops into the chamber 2, where further gas is generated, which passes to and causes the gasometer 26 to rise, as before described, and as the gas is consumed again the gasometer lowers, as well as the 85 ratchet-bar 27, which engages with and rotates the ratchet-wheel 23 and shaft 21, as before described. This moves the next succeeding pin in contact with the next succeeding sliding bar 15 to disengage it from shoulder 14 90 on the next succeeding carbid-case, which drops into the water in the chamber 2, and this is repeated so long as any carbid-cases remain charged. The gas passes from the gasometer 26 through the service-pipe 38 to the 95 burners.

The safety-pipes 41 and 42 permit the gas to escape to the outside of the building if more gas is generated than the gasometer will hold, or if the gasometer should not rise as the gas passes thereto in this case the gas would pass down through the branch pipes 35 and 39 and bubble up through the water and into the water-sealing chamber, from which it would escape through the secondary or supplemental safety-pipe 42. As a result a simple, strong, durable, safe, and economical machine for generating gas is provided. 100 105

Having thus described my invention, I claim—

1. In a machine of the class described, a carbid-case closed at its upper end, open at its lower end, and in one side of which an opening is formed, a carbide-holder open at the upper end, in the side of which perforations are formed, which is provided with a partition on which the carbide is placed, and which is supported and locked in place in said carbide-case, in combination with a pipe which is secured to said carbide-case, the opening in the side of the latter permitting the gas to pass from said case to said pipe, substantially as and for the purpose set forth. 115 120

2. In a machine of the class described, a carbid-case closed at its upper end, open at its lower end, and in one side of which an opening is formed, a carbid-holder open at the upper end, in the side of which perforations are formed, which is provided with a partition on which the carbid is placed and which is sup- 130

ported and locked in place in said carbid-case, and a pipe secured to said carbid-case, the opening in the side of the latter permitting the gas to pass from said case to said pipe, in combination with a conducting-pipe the upper end of which telescopes the pipe secured to the carbid-case, substantially as and for the purpose set forth.

3. In a machine of the class described, a carbid-case, a generator-tank, a shoulder secured to said carbid-case, a sliding bar provided with a flange and antifriction-roller, and a holder provided with antifriction-rollers for guiding and holding the sliding bar in line as it moves to or from said shoulder secured to said carbid-case in combination with a shaft provided with a ratchet-wheel and pins for operating said sliding bar and a ratchet-bar secured to the gasometer for revolving said ratchet-wheel as the gas is consumed, substantially as and for the purpose set forth.

4. In a machine of the class described, a carbid-case, a pipe secured thereto, a generator-tank, a flange secured to the interior face of said generator-tank, and curved recesses formed in said internal flange, to which said pipe is fitted and with which it is adapted to engage, in combination with a pipe telescoping with the pipe on the opposite side of the carbid-case, substantially as and for the purpose set forth.

5. In a machine of the class described, a carbid-case, a pipe secured thereto, a generator-tank, a flange secured to the interior face of

said generator-tank, and curved recesses 35 formed in said internal flange to which said pipe is fitted and with which it is adapted to engage, a pipe adapted to telescope with the other end of the pipe secured to the carbid-case, a shoulder secured to said carbid-case, 40 a sliding bar provided with a flange and antifriction-roller, a holder provided with antifriction-rollers, for guiding and holding the sliding bar in line, as it moves to or from said shoulder secured to said carbid-case, in combination with a shaft provided with a ratchet-wheel, and pins for operating said sliding bar, and a ratchet-bar secured to the gasometer, for revolving said ratchet-wheel, as the gas is consumed, substantially as and for the purpose set forth.

6. In a machine of the class described, a carbid-case, a pipe secured thereto and communicating therewith and a generator divided into two chambers by an inclined bottom in 55 combination with a pipe extending from and communicating with said chambers in said generator-tank and the upper end of said pipe telescoping into the pipe secured to the carbid-case, substantially as and for the purpose 60 set forth.

In testimony whereof I have signed in the presence of the two undersigned witnesses.

WILLIAM J. STINSON.
